UNITED STATES PATENT OFFICE.

JOHN E. NORWOOD, OF BALTIMORE, MARYLAND.

PISTON RING.

Application filed May 27, 1918. Serial No. 236,860.

To all whom it may concern:

Be it known that I, JOHN E. NORWOOD, a citizen of the United States, residing at Baltimore, in the county of Baltimore, State of Maryland, have invented certain new and useful Improvements in Piston Rings; and I do hereby declare the following to be a full, clear, and exact description of the invention, such as will enable others skilled in the art 10 to which it appertains to make and use the same.

The present invention relates to new and useful improvements in piston packings, more particularly of the type disclosed in 15 my copending application filed June 21, 1917, Serial No. 176,177, and particularly adapted for packing pistons of the combustion cylinders of explosive engines.

As in my co-pending application, the essential feature of the present invention is the provision of a packing ring structure which is expansile in nature both radially and laterally, to fit against the inner periphery of the cylinder and also to fit against both side walls of the piston groove in which it is disposed whereby to prevent leakage through the groove about the inner portion of the ring. To accomplish this essential feature, a pair of radially expansile ring 20 sections are provided, in cam engagement whereby the limitation of expanding movement of the larger ring sections by engagement with the cylinder wall will procure a lateral relative movement of the sections 30 for sealing engagement with the sides of the piston groove.

I have found in practice that this lateral sealing action of the piston ring structure against the side walls of the piston groove 40 is impaired by the high pressure within the cylinder on combustion, which enters the space between the body of the piston and the cylinder walls, at the head portion of the piston and exerts a force radially on the smaller packing ring section, compressing the section against its natural expansile resiliency, and thus destroying the sealing pressure exerted against the side walls of the piston groove through the cam action of such resiliency. Therefore the particular

object of my present invention is to lessen the contractile action of the combustion pressure in the cylinder upon the smaller laterally acting section of my ring structure, and I purpose to accomplish this object by so arranging the smaller ring section, and so forming its surface which is exposed to combustion pressure in the cylinder, that the force exerted by such pressure is directed obliquely to the direction of expansile and contractile movement of the ring section, and toward the adjacent wall of the piston groove so that the resultant inward force on the piston ring is exerted through the ring against said wall, to bind the ring 60 against compressive influence.

In the accompanying drawings:

Figure 1 is a sectional view taken longitudinally through a cylinder and piston of an explosive engine, having a ring structure 70 embodying the present invention disposed in the packing grooves thereof.

Figure 2 is an enlarged detailed sectional view taken transversely through one side of the ring and adjacent cylinder and piston 75 portions.

Figure 3 is a perspective view showing the ring cut in two.

Referring now more particularly to the accompanying drawings, 5 designates the cylinder of an explosive engine, having a closed head 6 and having slidable therein a piston 7 provided with the usual annular packing grooves 8 in its periphery, each groove being of the usual rectangular shape in cross section affording parallel side walls against which my improved packing ring is adapted to expand laterally for sealing engagement therewith. As in my said co-pending application each packing ring is composite in nature including a pair of annular sections 9 and 10, and the section 9 is preferably of the same form as shown in my said co-pending application, being of greater external diameter than the section 10 and also having a substantially greater general width, which is nearly equal to the width of its piston groove 8. The member 9 is beveled from its side face 11 adjacent the cylinder head 6 to its inner periphery 12 to form an under-

cut cam face 13, its ends being preferably provided with a lap joint 14. The section 10 is disposed at the cylinder head side 11 of the section 9 and is provided with a beveled 5 peripheral face 15, the inner portion of which is urged by the resiliency of the section into cam engagement with the undercut face 13 of the section 9, whose resilient expansion is limited by the wall of the cylinder and thus the resilience of the section 10 serves to urge both sections into sealing engagement with the sides of the packing groove. The beveled peripheral face of the section 10 meets the outer face 16 of said section 10 at an acute angle, and preferably at a line substantially coincident with the juncture of the adjacent side face of the groove and the periphery of the piston. 15

The expanding action of the ring sections 20 for sealing engagement with the wall of the cylinder and with the sides of the packing groove, is thus the same as in my aforementioned patent. When, however, the present ring structure is subjected to combustion 25 pressure passing between the piston and cylinder, the force of such pressure is exerted against the side face 11 of the major ring section 9 will only serve to press it more firmly against the groove side with which 30 it is in sealing engagement. At the same time, the pressure will exert a force against the ring section 10 tending to compress said section against the expanding force of its natural resiliency, but by reason of the bevel 35 of the outer portion of the peripheral face 15 of the section, such force will be exerted obliquely toward the side of the packing groove with which the section is in sealing engagement and not exerted directly inward, 40 as would be the case with all former structures for simultaneously effecting both a radial and lateral expansion of a composite packing ring with which I am acquainted. Thus the resultant of forces would be obliquely against the side of the packing 45 groove with which the section 10 is normally in sealing engagement, to bind the section against said side of the groove and to prevent its inward movement under influence 50 of combustion pressure. While the peripheral face 15 of the ring section 10 has been shown as provided with a single bevel, transversely flat throughout said face, it is obvious that any formation of this surface which 55 will procure a lateral camming action between the sections and which will procure a lateral direction of the force of combustion pressure exerted against its outer portion, may be employed. 60

I am aware that consideration has heretofore been taken of the action of working pressure in a cylinder upon the sections of a composite packing ring, and that there has been provided a composite packing ring having a section thereof beveled throughout its

entire peripheral surface and having the inner portion of that beveled surface in cam engagement with the other section of the ring. Both of these features are present in the patent to Swan No. 748,233, issued December 29, 1903, but in the structure of this patent an entirely different and opposite operation is procured, since it is the primary object of Swan's structure to provide for a lateral compression of the piston ring by the action of working pressure in the cylinder, this compression effecting a radial expansion of the normally inoperative ring, and exposing one side of the packing groove whereby gas could escape around the interior of the ring upwardly behind the piston through the joint of a ring section or between the other side of the groove and its adjacent ring section. One of the rings of Swan is contractile, while the other is solid and has no resiliency. Thus the patent to Swan compasses neither the object, nor provides the structure of my improved packing ring, which comprises a pair of sections, both resiliently expandable in nature. 70 75 80 85 90 95 100 105 110 115 120

What is claimed is:

1. The combination with the cylinder of an explosive engine and a peripherally grooved piston therein, of a composite ring comprising a radially expandible annular section within and of less width than the groove, and projecting from the groove into peripheral contact with the cylinder wall and having one end face contacting with a side wall of the groove and its other end face beveled to its inner periphery, the ring comprising also a second annular radially expandible section disposed between and contacting with the face of said bevel and the other side wall of the piston groove, the face of the second section that contacts with the beveled face of the first section being conical and continuous to the periphery of the piston where it meets the corresponding end wall of the section. 110
2. The combination with the cylinder of an explosive engine and a peripherally grooved piston therein, of a composite ring comprising a radially expandible annular section within and projecting from the groove into peripheral contact with the cylinder wall and having one end face contacting with a side wall of the groove and its other end face beveled to its inner periphery, the ring comprising also a second annular radially expandible section disposed between said beveled face and the opposite side wall of the piston groove with its end face disposed against said side wall, the outer periphery of the second section being beveled throughout its width to the angle of said bevel of the first section against which it is slidably disposed, said bevel and end face of the second section meeting substantially at the periphery of the piston and the bevel of

the second section being greater in width than that of the first section whereby a portion of the bevel of the second section is at all times accessible to gas pressure between it and the wall of the cylinder, in the direction of the groove wall with which the second section contacts.

In testimony whereof, I affix my signature, in the presence of two witnesses.

JOHN E. NORWOOD.
